UNITED STATES PATENT OFFICE.

CHRISTIAN WILKENING, HENRY WILKENING, AND LOUIS WILKENING, OF NEWPORT, KENTUCKY.

DESIGN FOR A FINGER-RING.

SPECIFICATION forming part of Design No. 13,296, dated September 12, 1882.

Application filed September 12, 1881. Term of patent 7 years.

To all whom it may concern:

Be it known that we, CHRISTIAN WILKENING, HENRY WILKENING, and LOUIS WILKENING, citizens of the United States, and residing at the city of Newport, in the county of Campbell and State of Kentucky, have invented and produced a new and original Design for Finger-Rings, of which the following is a specification, reference being had to the drawing forming a part thereof, which drawing is a perspective view of a finger-ring fashioned after our design.

Of late years there has been a growing demand for antique jewelry of various descriptions, and with a view of partially satisfying this demand we have produced the herein-described finger-ring.

Our design consists of a finger-ring having a square-shaped setting projecting above the

plane of the shank, and at the juncture of the shank with the setting is placed an antique face, the face extending partly on the shank and partly on the edge of the setting, as shown in the cut forming part of this specification.

What we claim as new, and desire to secure by Letters Patent, is—

A design for finger-ring, consisting of a plain shank and a square-shaped setting projecting above the plane of the shank, and an antique face placed at the juncture of the shank and the setting, substantially as described.

CHRISTIAN WILKENING.
HENRY WILKENING.
LOUIS WILKENING.
